ATTORNEY

UNITED STATES PATENT OFFICE.

JOHN W. FARLEY, OF CLEVELAND, OHIO.

PIPE-HANGER.

1,262,763.

Specification of Letters Patent. Patented Apr. 16, 1918.

Application filed July 16, 1917. Serial No. 180,756.

To all whom it may concern:

Be it known that I, JOHN W. FARLEY, a citizen of the United States, residing at Cleveland, in the county of Cuyahoga and 5 State of Ohio, have invented certain new and useful Improvements in Pipe-Hangers, of which the following is a specification.

This invention pertains to an improvement in pipe hangers, and the invention consists in a hanger which, in its simplest form, has the pipe supporting and gripping portions made of separable sections adapted to be conveniently assembled and separated, and which are self-locking and require no 15 bolts or screws or other extra devices to hold the parts together in operating relations.

In the accompanying drawings, Figure 1 is a perspective view of a double form of the hanger, adapted to engage or support 20 two pipes, one above the other, and in which the invention is practically duplicated.

Fig. 2 is a side elevation of the upper or main section as seen in Fig. 1 without the bracket at the top. Fig. 3 is a side elevation of the lower or coöperating section, 25 and Fig. 4 is a longitudinal central sectional elevation of the invention in its simplest form, consisting of two sections and as shown suspended from the upper holder in 30 Fig. 1.

A complete hanger, as thus shown, consists essentially of the two pipe gripping or engaging sections or members *a* and *b*. Of these the section *a* may be termed the main 35 or upper section or member, and the section *b* as the lower or auxiliary section or member, and both said sections or members are preferably made from a suitable grade of sheet steel, struck up by means of dies into 40 blanks of the desired shape or form and then bent flatwise at their lower ends into a substantially semi-circular shape but with length of curvature sufficient to overlap more or less in engagement upon a pipe.

Section *a* is duplicated in Fig. 1 barring a slight change in its lower end, and the said section has a flat body portion provided with a lengthwise slot or opening 3 starting a slight distance above its curved or bent 50 portion 5, while section *b* has a T shaped tongue 6 adapted to be entered through said slot and to be locked therein when turned

flatwise on section *a* to working position, as plainly seen in the drawings.

A feature of this self-locking mechanism 55 consists in the inward curvature or bend of the stem 7 of tongue 6, which brings the cross portion or wings of the tongue and the portion 8 below said stem 7 flatwise against opposite sides of shank 2, and when thus 60 engaged and section *b* is drawn down under the weight of the load the said section is really suspended through its own interlocking engagement with or through slot 3 and the pull thereon by the weight of the pipe is 65 carried by its own curved portion rather than by the portion 5 of the main section. However, in order to fix the working relations and engagement of said parts, I provide a lug or tooth 9 on the curved bottom 70 portion 10 of section *b* which engages in a corresponding hole 11 in the curved portion 5 of section *a* and thus further locks said parts together.

A pair of brackets 12 at the top of section 75 *a* serve to affix the same to a support, and if a second or third hanger is to be affixed to the first or upper hanger the said upper hanger is provided with an extension 15 at its bottom below the pipe engaging bend or 80 curve thereon. Otherwise the duplicated hangers in Fig. 1 are really alike.

What I claim is:

As a new article of manufacture, a pipe hanger consisting of a main part and an 85 auxiliary part formed from flat sheet metal and provided with segmentally curved pipe engaging portions in overlapped relations to support the pipe therein, and said main part having a flat upper portion provided with 90 a longitudinal slot and the auxiliary part having a T-shaped tongue adapted to be engaged through and interlocked with said slot, the stem of said tongue being bent at its passage through the slot to bring the cross 95 portion thereof and the flat portion of said part at its base flatwise against the flat sides of the main part of the hanger and the said main part having a hole above the slot 100 therein.

Signed at Cleveland, in the county of Cuyahoga, and State of Ohio, this 9th day of July, 1917.

JOHN W. FARLEY.
